(57) **CLAIM**

The ornamental design for a lighting fixture with a fitter portion, as shown and described.

DESCRIPTION

FIG. 1 is a front perspective view from above the lighting fixture with a fitter portion, with the fitter portion substantially aligned with the main portion of the fixture, a pole being shown in broken lines;

FIG. 2 is a perspective view from below the lighting fixture with a fitter portion of FIG. 1, the details of the underside of the fixture being shown in broken lines;

FIG. 3 is a right-side elevation view of the lighting fixture with a fitter portion of FIG. 1, the left-side elevation view being a mirror image thereof;

FIG. 4 is a bottom plan view of the lighting fixture with a fitter portion of FIG. 1, the details of the underside of the fixture being shown in broken lines;

FIG. 5 is a top plan view of the lighting fixture with a fitter portion of FIG. 1;

FIG. 6 is a front elevation view of the lighting fixture with a fitter portion of FIG. 1;

FIG. 7 is a rear elevation view of the lighting fixture with a fitter portion of FIG. 1;

FIG. 8 is a rear perspective view from above the lighting fixture with a fitter portion of FIG. 1, but showing the fitter portion in a position at 90° with respect to the main portion of the fixture, the pole being shown in broken lines;

FIG. 9 is a rear perspective view from below the lighting fixture with a fitter portion of FIG. 8, the details of the underside of the fixture being shown in broken lines; and,

FIG. 10 is a right-side elevation view of the lighting fixture with a fitter portion of FIG. 8, the left-side elevation view being a mirror image thereof.

The broken lines illustrate unclaimed portions of the lighting fixture with a fitter portion and environmental structure that form no part of the claimed design.
